(57) **CLAIM**

The ornamental design for a cup lid as shown and described.

DESCRIPTION

FIG. 1 is a top plan view of a cup lid, showing my new design;

FIG. 2 is a right side elevation view thereof, the left side elevation view being a mirror image;

FIG. 3 is a front elevation view thereof;

FIG. 4 is a rear elevation view thereof;

FIG. 5 is a bottom plan view thereof; and,

FIG. 6 is another perspective view thereof, shown in use with environmental subject matter of an exemplary cup. The broken lines are shown for the purpose of illustrating both parts of article, as well as environmental subject matter of an exemplary cup lid. None of the broken lines form part of the claimed design.

1 Claim, 3 Drawing Sheets
